UNITED STATES PATENT OFFICE.

LEVI BONNER, OF AMES, COLORADO.

ROTARY ENGINE.

No. 897,519.

Specification of Letters Patent.

Patented Sept. 1, 1908.

Application filed September 20, 1905, Serial No. 279,257. Renewed January 25, 1908. Serial No. 412,634.

To all whom it may concern:

Be it known that I, LEVI BONNER, a citizen of the United States, residing at Ames, in the county of San Miguel and State of Colorado, have invented a new and useful Improvement in Rotary Engines, of which the following is a specification.

My invention has relation to rotary engines of that type wherein a cylinder is rotated through the expansive force of steam or other expanding fluid or vapor, and particularly to an engine wherein the expanding vapor is admitted between a rotatable blade and a relatively fixed portion, or between two blades to rotate them in opposite directions.

The object of my invention is to provide a rotary engine of greater power than those now known,—of a simpler construction and of such form that it shall be particularly adapted to electrical work or to marine propulsion.

To this end it consists in the general construction and arrangement of parts and the combinations of elements described herein-after, and more specifically set forth in the claims appended.

I have illustrated my invention in the accompanying drawings, wherein

Figure 1 is a longitudinal elevation of the engine. Fig. 2 is a longitudinal section on the line $x-x$ Fig. 3. Fig. 3 is a diametric section of the cylinder on the line $y-y$ Fig. 2 looking towards the head of the larger cylinder. Fig. 4 is a diametric section on the line $w-w$ Fig. 2. Fig. 5 is a diametric section on line $z-z$ Fig. 2.

Throughout the several views like numerals designate like parts.

The main feature of my engine is comprised in an inner and outer cylinder, numbered 2 and 3 respectively, one rotating about the other, each of the cylinders being provided with resilient bladelike valves, which co-act with each other and against the adjacent surface of the other cylinder all as will be later described.

The cylinder 2 has a smooth, unbroken interior surface and while it may be of any suitable construction I believe it best to make it as I have shown clearly in Fig. 1 namely, one end and the drum in one part, to which the other end, forming a head 2', is removably bolted. The head 2' of the cylinder has at

its center an outwardly projecting hollow hub 20 which forms a bearing for the shaft 3' of the inner cylinder 3 and is itself borne in journal or pillow box 2" on a standard or support 2''. The other end of the outer cylinder 2 carries also a central hollow shaft 4' which is adapted to rotate in a steam chest and be supported at its end in journal bearings 4" on standards 4''. This hollow shaft forms a bearing for the shaft 3" of the inner cylinder. The cylinder 3 and its shafts 3' 3" 65 may be rotary or stationary as will be later described. I have shown these shafts as continuous but they may be made separate.

Referring now particularly to Figs. 3, 5 and 6 are wing valves and propelling blades resiliently set on the inner and outer cylinders and adapted, by reason of their resiliency, to pass each other when they meet and during the remainder of the revolution to press upon the face of the opposite cylinder. Thus the 75 blade 5 attached to the interior of the outer cylinder elastically presses inward against the circumference of the inner cylinder, while the blade 6 attached to the inner cylinder presses out against the outer cylinder, 80 the contact being so close and firm that no steam or vapor can pass between the edge of the blades and the cylinder wall.

While any form of resiliently mounted blade is within my invention, I preferably 85 mount the blades in spring clips 5' 6' which are attached to the faces of the cylinders. These clips extend longitudinally the whole of the cylinder length and are bent over so as to form a longitudinal fold, within which the 90 folded inner edge of the blade is held. By this construction the blades may be slipped into place from one end of the cylinder through a hand hold 2''' there located for that purpose, thus allowing the adjustment 95 of the blades, or their replacing when worn out.

It is to be noted that the blades 5 and 6 are inclined in the same direction to each other; a direction backward from the direction of rotation of the respective cylinders and that thus when two opposite blades meet they mutually give or slide over each other with a wedging action until they pass, when each one springs toward the face of the 105 opposite cylinder and into the position shown in Fig. 3. It is to be kept in mind that while I show in Fig. 3 a double rotary engine with

two revolving cylinders, an inner and outer, the inner cylinder may be stationary and the blade act as a fixed face against which the steam pushes. The principle of operation is the same in either of these cases.

In order that steam or other expanding vapor shall turn one cylinder in relation to the other, it is necessary immediately after their blades have met and passed each other, 10 that the steam or vapor be admitted to the space between them, which being done, the two blades will be forced apart. To this end I provide a vapor inlet or inhaust port 7 which opens into the space between the two 15 cylinders, and at its other end communicates with a suitable source of steam or vapor supply, the inlet port being provided with some means for cutting off the supply of vapor at a predetermined point. Preferably, the in- 20 haustrum opening 7 forms the termination of a passage 7' formed in the end of the cylinder 2 which passage extends towards the center of the cylinder end and then passes at right angles along through the wall of shaft 4 a suit- 25 able distance when it passes out to the circumference of the shaft at 7" where it aligns with the inlet openings of the steam chest 11.

9 designates an exhaust outlet which forms the extremity of a radial passage 9' which ex- 30 tends inward to a point near the central shaft 3" and inside the ring 8' where it turns parallel to said shaft and opens into a semi-circular groove 9" formed on the outer face of the cylinder head 3". This groove regis- 35 ters with the opening of a passage 10 which leads along shaft 4 to a point beyond the plane of the vapor inlet openings of the steam chest. At this point it turns outwardly and has an opening 10' on the outside of the 40 shaft, in the same manner as before de- scribed for the inhaust passage. It will be thus seen that as regards the shaft 4, the in- let and outlet passages are diametrically op- 45 posite to each other, though by reason of the passage 9' taking off at the extremity of the semi-circular groove 9", the exhaust outlet opening in the cylinder is located directly be- 50 hind the blade on the inner cylinder. There is another object in having this groove semi- circular. If the passage 9' merely opened directly to the outer face of head 3" it would only align with the passage 10 at one point in its revolution and then but for an instant. By carrying the groove in the arc of a circle 55 around the center of rotation, the passage 9' will be in connection with passage 10 during a period of revolution depending upon the length of the groove.

11 designates a steam chest of any suitable 60 construction through which the shaft 4 passes and in which it rotates. In vertical alinement with the inhaust inlet port of the shaft 4 are entrance passages 12, 13 which are connected by pipes 12' 13' to any suitable source 65 of vapor supply as to a steam boiler as shown

in Fig. 4. In vertical alinement with the exhaust outlet port are exit passages 14 15 which are connected to suitable leading off pipes 14' 15' as shown in Fig. 5. Preferably I use a common steam pipe 12" for both 70 steam inlets, connecting the lower steam in- let pipe 13' to the pipe 12" by a by-pass pipe 13", having therein the cut off valve 13". The main steam pipe 12" has in it a cut off valve 12"". By closing the valve 12"" the 75 steam is entirely cut off from the engine, and by closing valve 13"" steam is cut off from the low inlet. This is done when the engine is working singly and the inner shaft 3" and its cylinder is fixed from turning. A similar 80 arrangement of pipes 14", 15", 15" with cut off valves is used for the exhaust connections.

So far as I have described the mechanism of my engine the vapor would enter the cylinders at one or two points and be imme- 85 diately cut off and the exhaust ports would be likewise opened and immediately closed by the passage of the ports past each other. In order to provide for the admission of vapor to the cylinder during a predetermined arc of rota- 90 tion, I extend the entrance passages 12 or 13 in the form of a groove circumferentially around the interior of the steam chest. While these grooves are shown as extended 95 around the steam chest I wish it understood that they might be transposed and formed in the shaft 4 except that if they were of any length they would weaken the same too much. There would be, however, no varia- 100 tion of principle or change in the operation. For the same reason, that is in order that the exhaust may continue through a certain length of time, I extend the exhaust passage 14 as grooves around the inner circumference 105 of the steam chest. It will thus be seen that during that portion of a rotation during which one of the inhaust passage grooves has any portion of it opposite to a shaft port, vapor will be taken into the cylinder, and that when the end of the shaft port passes the entrance groove the shaft port will be closed and the vapor will be cut off, and that the same thing occurs as regards the exhaust. Thus by regulating the length of the inhaust 110 and exhaust groove in the steam chest any 115 length of vapor intake or outlet may be pro- vided for. The cylinder may take steam for the whole of its rotation, for two thirds, one half or any fraction thereof, and the exhaust be opened for any predetermined part of the 120 rotation, in the same manner.

When the engine is worked double, both cylinders rotating, it is necessary that the cylinders should take steam twice during each revolution, once after each passing of the blades. In that case the position of the exhaust and inhaust ports are as shown in Figs. 4 and 5, the inlets and outlets being diametrically opposite each other. In Fig. 4 I have shown these inhaust grooves of a 130

length sufficient to provide for the entrance of steam during one third of a "stroke",—or the arc of rotation passed over by the wings before they meet,—assuming that the engine 5 is running double. If the engine is run single, that is with only the outer cylinder in rotation, the inhaust should be lengthened as shown in dotted lines to give an entrance of steam during one third of a revolution, thus 10 allowing the steam to be used expansively over two thirds of the cylinder space. The exhaust grooves I have also shown as being one third the length of the stroke, and on the left hand side of Fig. 5 I have shown in dotted lines the exhaust groove as extended to one third the entire circumference.

In the arrangement shown in the drawings the cylinder will receive steam for one sixth of its rotation, will hold the steam for two 20 sixths and will exhaust during the next sixth. Immediately after passing at the lowest part of the cylinder the blades again receive steam between them for a sixth of a revolution, holding it for a sixth and again exhausting. 25 In this connection it may be well to point out what is easily lost sight of, that the inlet port 7 and the exhaust port 9, is located each behind a blade and that they turn each with its cylinder. The position of the blades, inhaust 30 opening and exhaust opening, at the lowest points of the revolution, after the blades have passed each other and are taking steam between them, is precisely the position shown in Fig. 3, only reversed.

When two oppositely rotating cylinders are used it becomes necessary to so gear the two shafts that power may be taken from them both. This may be done in a number 35 of ways which will readily suggest themselves to the practical mechanic; but as one means of accomplishing this I use the combination of bevel gears shown in Fig. 2. The end of the outer shaft 4 is extended beyond the bearing and carries a bevel gear 16 which, 40 of course, is loose on the shaft 3". The shaft 3" passes through the bevel gear 16' splined thereon. These two bevel gears mesh on opposite sides with an intermediate loose bevel gear 17 which forms the end of a 45 sleeve 17'. This sleeve and bevel gear surround a central fixed shaft 18 about which it rotates. The lower end of the sleeve 17' is cut to form a cam face which engages with a rotatable cam 18' supported on a standard 50 18". The loose bevel gear 17 is merely for the purpose of intermeshing the shafts 3" and 4 so that they shall run together. When the engine is running singly, that is with only the outer cylinder revolving, it is necessary 55 to that the shafts 3" and 4 be disengaged. In that case the cam 18' is turned to lower the gear 17 away from intermeshing with gears 16 16'. It is to be understood that I may use any of the well known methods and 60 mechanisms for accomplishing this result and

merely show the particular construction described because of simplicity. There are many ways by which this result may be accomplished which will be apparent to any mechanic. It will be seen that this combination takes power from both shafts, thus keeping the cylinders running evenly together. When the engine is running singly it is necessary that the inner cylinder should be held stationary with its blade up. In 70 order to provide for this I provide a clutch mechanism capable of engaging with the shaft 3" to hold it and the cylinder 3 stationary. I have shown such a clutch mechanism in Fig. 2 wherein 19 is a clutch lever 75 suitably mounted and having projections or teeth 19' which will engage with recesses 16" in bevel gear 16'. In the position shown in Fig. 2, the clutch lever and its teeth are out of engagement with gear 16'; when the lower 80 end of the lever is moved inward against said gear the teeth will engage with the recesses to hold the shaft 3" in one position. There are many forms of clutch which could be used for this purpose and I do not wish to 85 limit myself to the construction just described. It is only necessary that some means be provided whereby the shaft 3" shall be held positively from turning when the engine is to be run singly.

In Fig. 2 I have shown the gear 17 and the clutch 19 both out of engagement at the same time. I show it in this manner for clearness of illustration but it is to be understood that the clutch could be thrown into 90 engagement with gear 16' when the loose gear 17 is moved out of engagement.

21 21' indicate pulleys or belt wheels fast respectively on shaft 3" and on the hollow hub 20 which projects from and forms part 105 of the head 2' of cylinder 2. When the engine is running double the central shaft and its surrounding hub move, of course, in opposite directions. Power may be taken from either of the pulleys 21 or 21' and by shifting 110 the belt from one to the other the power may be reversed without reversing the engine.

In order to run the joint between the cylinder ends vapor-tight, I provide an anti-friction packing ring or rings 22 at each end 115 of the inner cylinder which fit in corresponding grooves in the adjacent walls of the cylinder ends, thus allowing the end walls of the cylinders to be separated slightly and decrease 120 the friction. I also provide a packing ring 23 between the inhaust and exhaust valve-grooves of the steam chest to prevent the steam or other vapor escaping from the inhaust groove to the exhaust.

While I have shown for clearness only the main and requisite elements of the engine, in practice, of course, it will be provided with proper stuffing boxes, lubrication inlets, cut-off valves, etc. and the shafts with transmis- 130

sion gears. These being well known and thoroughly understood by all conversant with engines it need not be specifically described.

5 While I have described my engine as using steam as the expanding vapor whereby it is to be driven, yet I may use any other elastic fluid as hot air, or use the expanding force of exploding vapor, as that of gasoline, equally 10 well, and I wish it understood that this is within my invention. The rotary form of engine would be particularly well adapted to making the proper sparking connections in its use as an explosive engine. The exact 15 form and arrangement of parts, however, whereby this rotary engine is adapted to be used as an explosive engine, I design to form the subject of a later application.

It is to be noted that in order to run the 20 double oppositely rotating cylinders as a single engine, all that is necessary to do is to close the lower steam port and the upper exhaust port, disconnect the bevel gearing on the end of the shaft 3 from contact with the 25 intermediate bevel gearing which normally engages with said bevel gear, and by the clutch 20 21 hold the inner cylinder from movement.

It is obvious, of course, that the exhaust 30 and inhaust passages and connections might be at opposite ends of the outer cylinder without departing from my invention. I have in the claims called for the cylinders as rotative relative to each other. This phrase 35 is intended to include within it a positively fixed cylinder and a rotative one, as well as the two oppositely rotating cylinders.

Having described my invention what I claim is:

40 1. A rotary engine having outer and inner cylinders, one of which has a movement of rotation relative to the other, a resilient blade attached to one of said cylinders whose edge bears on the circumferential surface of 45 the other cylinder, and fluid pressure inlets and outlets opening into the space between the said cylinders, said blade being rearwardly inclined and the faces thereof against which the pressure acts being inclined to the 50 face of the cylinder against which it contacts, substantially as described.

2. A rotary engine having an interior and exterior cylinder one of which has a movement of rotation relatively to the other, a 55 silent, rearwardly inclined blade mounted on the interior face of the outer cylinder and normally bearing against the face of the inner cylinder, a resilient, rearwardly inclined blade mounted on the inner cylinder and normally bearing against the inner face of the outer cylinder the faces of both of said 60 blades against which the pressure acts being inclined to the face of the cylinder against which it contacts, means whereby the said 65 blades shall pass each other when they meet,

and fluid pressure inlets and outlets opening into the space between said cylinders, substantially as described.

3. A rotary engine having inner and outer cylinders one of which has a movement of 70 rotation relatively to the other, a blade resiliently mounted on the inner face of the outer cylinder, inclined reversely to the direction of rotation and normally bearing against the outer face of the inner cylinder, a corresponding blade mounted resiliently on the inner cylinder and inclined rearwardly to the direction of rotation of said cylinder and normally bearing against the inner face of the outer cylinder the faces of both of said blades 80 against which the pressure acts being inclined to the face of the cylinder against which each blade contacts, and fluid pressure inlets and outlets opening into the space between said cylinders, substantially as described. 85

4. In a rotary engine the combination with an interior and exterior cylinder, having ports for the admission of fluid pressure between them, of a blade mounted upon one of 90 the said cylinders and adapted to fill the space between the said cylinders, said blade being mounted upon said cylinder by means of a spring clip whereby it may be removed or replaced, substantially as described. 95

5. In a rotary engine the combination with an interior and exterior cylinder, having ports for the admission of fluid pressure between them, of a blade mounted upon one of the said cylinders and adapted to fill the 100 space between the said cylinders, said blade being mounted upon said cylinder by engagement with a longitudinal clip extending the length of said cylinder, whereby the blade may be removed or replaced, substantially 105 as described.

6. A rotary engine having an inner and an outer cylinder mounted to have opposite rotation each relative to the other; a blade mounted on one cylinder and bearing against 110 the other; a hollow shaft leading from one end of said outer cylinder and forming the axis of rotation therefor; an inner shaft on which the inner cylinder is mounted, passing through the hollow outer shaft; a fluid pressure inlet port in said outer shaft; a passage leading from said port to the annular space between the said cylinders and opening behind one of said blades; an exhaust port in said shaft; a passage leading to the space between the outer and inner cylinders and opening in front of the other of said blades; and means for admitting the fluid to said inlet port, substantially as described. 115

7. A rotary engine having an inner and outer cylinder mounted to have opposite rotations relative to each other, blades mounted on each cylinder each bearing normally against the opposite cylinder and adapted to 120 pass each other, a hollow shaft leading from 125

one end of said outer cylinder and forming the axis of rotation therefor; an inner shaft on which the inner cylinder is mounted, passing through the hollow outer shaft, a fluid pressure or inlet port in said outer shaft, a passage leading from said port to the annular space between the said cylinders, an exhaust port in said shaft, a passage leading therefrom to the cylinder head, said head having 10 a passage whose port registers with said exhaust shaft passage, the passage in said head opening on the outside of said inner cylinders, and an inlet port behind one of said blades, substantially as described.

15. 8. A rotary engine having inner and outer cylinders rotatably mounted relatively to each other, a blade attached to one of said cylinders whose edge bears on the adjacent face of the other cylinder, an axial tubular shaft on which the outer cylinder is mounted, a shaft for the inner cylinder extending through the said tubular shaft concentric thereto, inlet and outlet ports in the said outer shaft, passages leading therefrom to 20 the space between the inner and outer cylinders, and gearing between the two shafts whereby their relatively opposite motion may be transformed in the rotary motion in one direction mechanism whereby the connection between the two shafts may be 25 broken, and means for holding the inner cylinder and its shaft from rotation, substantially as described.

9. A rotary engine having an exterior cylinder and an interior cylinder entirely closed 30 mounted to rotate in opposite directions relatively to each other, a resilient blade on the outer cylinder adapted to fill the space between the said cylinders and contacting with the inner cylinder, a resilient blade on the inner cylinder filling the space between the said cylinders and contacting with the outer cylinder, means whereby the said blades shall pass each other at their meeting points, 35 the outer cylinder being provided with an inlet port in its end whereby fluid pressure may be introduced between the said blades immediately after their passage, and one of said cylinders being provided with a continuously open exhaust port substantially as described.

10. A rotary engine having interior and exterior cylinders mounted to rotate in opposite directions relatively to each other, a resilient, rearwardly extending blade on the outer cylinder the faces whereof against which the pressure acts being inclined to the face of the cylinder against which the blade contacts adapted to fill the space between the said cylinders and contacting with the inner cylinder, a resilient, rearwardly extending blade on the inner cylinder filling the space between the said cylinders and contacting with the outer cylinder the face of said 60 blade against which the pressure acts being

inclined to the face of the cylinder against which it contacts, means whereby fluid pressure may be introduced between the said blades immediately after their passage, means whereby the said fluid pressure may be cut off at any predetermined period of cylinder rotation, and means whereby the fluid may be relieved at any predetermined point in the cylinder rotation, substantially as described. 70

11. A rotary engine having interior and exterior cylinders mounted to rotate in opposite directions relatively to each other, a blade on the outer cylinder adapted to fill the space between the said cylinders and contacting with the inner cylinder, a blade on the inner cylinder filling the space between the said cylinders and contacting with the outer cylinder, means whereby the said blades shall pass each other at their meeting points, a port in the end of the outer cylinder adapted to allow the inlet of fluid into said space between said cylinders and behind said blades immediately after the blades have passed each other and the port, means for keeping said port open during a predetermined part of the cylinder rotation, an exhaust port located in the inner cylinder and opening in front of the blade attached thereto, and means for keeping the said exhaust port open during a part of the cylinder rotation, substantially as described. 75 80 85 90 95

12. A rotary engine, having inner and outer cylinders rotatably mounted relatively to each other, elastically held driving blades on each cylinder adapted normally to project across the space between the two cylinders and to contact with the opposite cylinder face and to resiliently yield when passing each other, a tubular shaft on which the outer cylinder is mounted, a central shaft within said tubular shaft on which the inner cylinder is mounted, a fluid pressure inlet passage in the outer shaft opening at one end into the space between the outer and inner cylinders and behind the outer cylinder blade, and at its other end opening to the outer face of said shaft, a valve chest surrounding said shaft and having a circumferential groove extending therearound in the arc of a circle, a connection between said 100 105 110 115 groove and a source of steam supply, and an exhaust passage leading from the space between the cylinders adapted to open at a predetermined point in the cylinder rotation for the discharge of the exhausted vapor, substantially as described. 120

13. A rotary engine, having inner and outer cylinders rotatably mounted relatively to each other, elastically held driving blades on each cylinder adapted normally to project across the space between the two cylinders and to contact with the opposite cylinder face and to resiliently yield when passing each other, a tubular shaft on which the outer cylinder is mounted, a central shaft 125 130

- within said tubular shaft on which the inner cylinder is mounted, a fluid pressure inlet passage in the outer shaft opening at one end into the space between the outer and inner cylinder behind the outer cylinder blade, and at its other end opening to the outer face of said shaft, a steam chest surrounding said shaft and having a circumferential groove extending therearound in the arc of a circle, a connection between said groove and a source of steam supply, an exhaust passage in the outer shaft opening at one end into the space between the two cylinders and leading along said shaft and opening to the outside thereof at a point out of vertical alinement with the steam chest opening of the inlet passage, and a groove in the said steam chest in vertical alinement with said exhaust port opening, said groove being extended circumferentially around said shaft in the arc of a circle, substantially as described. 10
14. In a rotary engine, an exterior revolving cylinder, an interior cylinder within the outer cylinder, driving blades in the cylinders filling the space between the two cylinders and adapted to pass each other, means for introducing an expansible fluid between the blades to rotate the cylinders in opposite directions, a tubular shaft extending from said outer cylinder, and forming the axis thereof, a central shaft extending from the inner cylinder and carried within the tubular shaft and projecting beyond the same, a bevel gear on the end of the outer shaft, an oppositely faced bevel gear on the end of the inner shaft, and a bevel gear meshing with both of said first named gears and taking rotation therefrom, and a means for reversing the motion transmitted from said intermediate bevel, a clutch for throwing said gears out of engagement with each other and means for holding the central shaft and its cylinder from movement, substantially as described. 20
15. A rotary engine having the inner and outer cylinder mounted to have opposite rotation relative to each other, resilient blades mounted on both cylinders and bearing against the other, the fluid pressure or inlet port leading into one of said cylinders and opening behind the blade of that cylinder, an exhaust port in the other of said cylinders opening in front of the blade attached to said cylinders and connections between said inlet port and a source of fluid pressure. 30
16. In a rotary engine having two cylinders mounted to have opposite rotation relative to each other, a resilient blade carried by one of said cylinders and bearing against the other, said blade being reversely inclined to the direction of movement of the cylinder to which it is attached, the face of said blade against which the pressure acts being inclined to the face of the cylinder against which it contacts. 40
17. In a rotary engine an exterior cylinder, and an interior cylinder, one of which is free to revolve relatively to the other, driving blades on the two cylinders filling the intermediate space and adapted to pass each other, a fluid inlet passage in the head of the outer cylinder opening into the cylinder-space behind the blade carried by said outer cylinder, and a fluid outlet passage in the inner cylinder opening into the cylinder-space before the blade carried by said interior cylinder, substantially as described. 50
18. In a rotary engine, an exterior rotatable cylinder mounted on a hollow shaft rotatable therewith, an interior cylinder mounted on a shaft carried within the hollow shaft, heads for said cylinders having contacting end faces, driving blades on the two cylinders filling the intermediate space and adapted to pass each other, a fluid inlet passage in the head of the outer cylinder opening at one end into the annular space between the cylinders and behind the blade carried by the outer cylinder extending along said shaft and opening into a steam inlet chamber, an exhaust passage in the head of the inner cylinder having an opening at one end into the space between the cylinders, and at the other end opening into a groove in the face of the inner cylinder-head concentric to the axis of rotation of the two cylinders, and an exhaust passage along the outer shaft, one end of which is in concentric alinement with said groove and the other end of which opens in the exhaust chamber, substantially as described. 60
19. In a rotary engine an exterior rotatable cylinder, mounted on a hollow shaft rotatable therewith, an interior cylinder mounted on a shaft carried within the hollow shaft, heads for said cylinders having contacting end faces, driving blades on the two cylinders filling the intermediate space and adapted to pass each other, an inlet passage in the head of the outer cylinder opening at one end into the annular space between the cylinders behind the blade carried by the outer cylinder extending along said shaft and opening into the steam inlet chamber extending circumferentially partly around said shaft, an exhaust passage in the head of the inner cylinder having an opening at one end into the space between the cylinders and at the other end opening into a groove in the face of the inner cylinder head concentric to the axis of rotation of the two cylinders, and an exhaust passage along the outer shaft one end of which is in concentric alinement with the said groove and the other end of which opens into an exhaust chamber in the steam chest, said chamber forming a partly circumferential groove around said shaft, substantially as described. 70
20. In a rotary engine, an exterior rotatable cylinder and an interior rotating cylinder, whose heads contact at their end faces, 80
- 100
- 110
- 120
- 125
- 130

driving blades on the two cylinders filling the intermediate space and adapted to pass each other, a hollow shaft on which the outer cylinder is mounted, a vapor chest having 5 semi-circular inlet grooves diametrically opposite to each other in the same plane, and semi-circular outlet grooves diametrically opposite to each other in the same plane, said grooves partly surrounding said shaft, 10 an inlet passage in the head of the outer cylinder opening at one end into the annular space between the cylinders behind the driving blades of the outer cylinder extending along said shaft, an opening on the surface 15 of the shaft in plane with the inlet grooves of the vapor chest, an exhaust passage in the head of the inner cylinder having an opening at one end into the space between the cylinders before the driving blade of the inner cylinder and at the other end opening into 20 a groove in the face of the inner cylinder head concentric to the axis of rotation of the two cylinders, an exhaust passage along the shaft of the outer cylinder one end of which 25 is in concentric alinement with the said groove and the other end of which opens on the outer face of the shaft in alinement with the said circumferential outlet grooves, a main inlet vapor pipe having branches leading 30 to the two inlet grooves of the vapor chest, valves in the branches for checking

the admission of vapor to either or both of the grooves and a main vapor exhaust pipe having branches leading from the two outlet grooves and having valves therein whereby 35 either of the branches may be cut off from the main outlet pipe, substantially as described.

21. In a rotary engine, an inner and an outer cylinder mounted to have opposite rotations, oppositely projecting blades on said cylinders contacting with the opposite cylinder, means whereby pressure may be admitted between the said cylinders and between the blades to act against the same, 45 means for allowing the exhausted pressure to pass out of said cylinders, mechanism for translating the opposite rotary motions of the two cylinders into motion in one direction, mechanism for disconnecting one of 50 said cylinders from the other and means whereby one of said cylinders may be held from movement.

In testimony whereof, I have signed my name to this specification in the presence of 55 two subscribing witnesses, this 29th day of August A. D. 1905.

LEVI BONNER.
